Robert Burns.
ATTORNEY.

UNITED STATES PATENT OFFICE.

JOHN J. PROCHAZKA, OF CHICAGO, ILLINOIS.

BOILER AND FURNACE ASH-PAN.

1,277,751.

Specification of Letters Patent. Patented Sept. 3, 1918.

Application filed December 7, 1917. Serial No. 205,937.

To all whom it may concern:

Be it known that I, JOHN J. PROCHAZKA, a citizen of the United States of America, and a resident of Chicago, in the county 5 of Cook, State of Illinois, have invented certain new and useful Improvements in Boiler and Furnace Ash-Pans, of which the following is a specification.

This invention relates to that class of ash 10 pans used in connection with the ash pits of house heating furnaces and boilers and has for its object:—

To provide a structural formation and association of parts, whereby all the ashes 15 that drop from the grate are directed into a pan or receiver of convenient size, thereby avoiding dust and the use of a shovel in removing the ashes, and whereby a removal of the appliance can be conveniently accomplished where through neglect of the attendant, the ash pit of the furnace becomes 20 unduly filled with ashes, all as will hereinafter more fully appear.

In the accompanying drawings:—

25 Figure 1, is a perspective view of an ash pan having the present improvement applied.

Fig. 2, is a detail perspective view of one 30 of the deflector plates in a detached condition.

Fig. 3, is a similar view of one of the pivot rods.

Fig. 4, is a horizontal sectional view 35 showing the present ash pan structure in place in a furnace ash pit.

Fig. 5, is a transverse section of the same on line 5—5, Fig. 4, like reference numerals indicate like parts in the several views.

Referring to the drawing, 1 designates 40 the vertical inclosing wall as a furnace ash pit of a round or other usual form, and having an entrance opening or doorway 2, as shown.

3 designates an ash pan of the usual open 45 top, and preferably formed with straight and parallel side walls as shown. The present improvement involves in connection with the above described or usual construction of a furnace ash pit and removable 50 ash pan, a detail structure as follows:—

4 designates a pair of deflector plates movably associated with opposed side walls

of the ash pan 3 by detachable hinge connections as follows:

6 and 7 designate interengaging pivot 55 knuckles or eyes, formed on one edge of each deflector plate 4 and on an edge of each side wall of the ash pan 3, and adapted to receive a pivot rod 8 by which the parts are connected together in a pivotal manner, 60 capable of disassemblage by the removal of said pivot rod. To such ends said pivot rod is provided with an operating handle 9 of any usual form for convenient manipulation. 65

In the preferred construction shown, the pivot rod 8 is formed with a non-circular portion 10 adapted to engage in a similarly formed outer knuckle 7" of a deflector plate 4 to provide an operative connection whereby a swinging movement of said deflector plate 4 can be attained by a corresponding turning movement of said pivot rod by the operator. 70

In actual use, and with the ash pan 3 in 75 place in the ash pit, the deflector plates 4 are turned into an inclined position with their free ends resting against the side walls of the ash pit as shown. When it is desired to remove the ash pan, the deflector 80 plates 4 are turned over onto the top of the ashes in said pan, to cover and inclose the same, after which the ash pan is withdrawn from the ash pit for the ordinary dumping operation. When through neglect on the 85 part of the attendant the ashpit becomes unduly filled and clogged up with ashes, thus preventing a local operation of the deflector plates and a removal of the ash pan with said plates connected thereto, the present improvement affords a ready means for overcoming the difficulty, by a removal of the pivot rods 8, so as to permit of a separate withdrawal of the ash pan proper, a subsequent withdrawal of the deflector plates and a removal of the surplus ashes in the ordinary manner. 90

11 designates bent wings formed on the free forward corners of the deflector plates 4, adapted on a closure of said plates to embed themselves in the top portion of the ashes to more effectually retain said deflector plates in place over the body of ashes. 95

Having thus fully described my said in-

vention, what I claim as new and desire to secure by Letters Patent, is:—

The combination with an ash pan of the type described, of a pair of deflector plates 5 pivotally associated with the side walls of the ash pan, and longitudinally removable pivot rods constituting the pivot connections

between said pan and plates, said rods being removable when the ash pan is within the ash pit to permit a separation of the plates 10 from the pan substantially as set forth.

Signed at Chicago, Illinois, this 30th day of November, 1917.

JOHN J. PROCHAZKA.
